UNITED STATES PATENT OFFICE.

JOHN R. DEAN, OF NORTH GIRARD, PENNSYLVANIA.

WIRE-BENDING MACHINE.

1,113,104.

Specification of Letters Patent.

Patented Oct. 6, 1914.

Application filed September 26, 1911. Serial No. 651,348.

To all whom it may concern:

Be it known that I, JOHN R. DEAN, a citizen of the United States, residing at North Girard, in the county of Erie and State of Pennsylvania, have invented new and useful Improvements in Wire-Bending Machines, of which the following is a specification.

This invention relates to wire bending machines and consists in certain improvements in the construction thereof as will be herein-after fully described and pointed out in the claims.

The machine is peculiarly adapted for bending wires into the form of garment stays and as shown is arranged for this purpose.

The invention is illustrated in the accompanying drawings as follows:

20 Figure 1 shows a front elevation of the machine, partly in section on the lines 1—1 in Figs. 2 and 3. Fig. 2 a plan view of the machine. Fig. 3 a section on the lines 3—3 in Figs. 1 and 2. Fig. 4 a section of a part 25 of the machine on the lines 4—4 in Figs. 1 and 3. Fig. 5 a central section of the shuttle on the line 5—5 in Fig. 3. Fig. 6 a central section through the flattening rolls on the line 6—6 in Fig. 2. Fig. 7 a fragment 30 of a stay formed of a plurality of wires. Fig. 8 a fragment of a stay formed of a single wire.

1 marks the base plate of the machine. This is mounted on the legs 2. A guide plate 3 is secured to the base plate by bolts 4. The guide plate has the cut-out portions to form the guide ways 5. The inner edges of the guide ways are formed by the plates 6. The plates 6 are mounted on the 40 shafts 7 and are secured thereon by means of set screws 8. The shafts 7 extend through the perforations 9 in the posts 10, and are secured in place therein by the set screws 11. The posts 10 are secured to the base plate 1 by the bolts 12. By adjusting the shaft 7, the plates 6 may be brought into the same plane with the plate 3. The shaft is so located as to bring the plates 6 into such position as to make their edges parallel with 50 the edges of the opening in the guide plate 3 so as to form the guide ways 5.

Forming pins 13 are carried by the plates 6 at each side of the crossing and are spaced a distance apart to give the proper width to 55 the fabric. These pins are L-shaped having an outwardly extending portion extending in an axial direction on which the wire is

formed and a laterally extending portion which affords a means for fastening the pins. The lateral portion is clamped on a deflecting plate 14 by means of a clamping plate 13^a, the clamping plate being secured in place by screws 13^b. This shape of forming pin is important in that it is subjected to constant strain and at the same time, the 60 forming pins must be of very small diameter to give the loops of the stay such a diameter as is ordinarily desired.

The deflecting plate 14 is adjustably secured on the plate 6 and by adjusting this 70 plate, the width between the pins 13 may be adjusted. The plate 14 is provided with a slot 14^a through which extends a screw 14^b, the screw entering the plate 6. An adjustable screw 14^c extends through a web 14^d on 75 the plate 14 into the plate 6, the screw having the shoulders 14^e at each side of the web to lock the screw against axial movement with relation to the web. By loosening the screw 14^b, and then turning the screw 14^c, 80 the plate 14 may be moved to any desired position giving the desired position to the pin 13, and then locked in position by tightening the screw 14^b.

The deflecting plates 14 have an off-set 85 at the crossing permitting the part of the shuttle 16 on the outer face of the guide plate to pass under it. As shown, the machine is designed to form a fabric of three wires, and three shuttles 16^a, 16^b and 16^c are 90 shown. The shuttle is shown in detail in Fig. 5. It has the two guide plates 17 and 18, the guide plate 17 being arranged on the face of the plate 6 from which the forming pins extend, and the plate 18 being on the 95 back side of the guide plate. These plates 17 and 18 are of greater width than the guide slot 5 so that they at all times overlap the surfaces of the plates 3 and 6. The plates are united by the pins 19, the pin being headed into the plate 17 and secured to the plate 18 by means of the nut 20. This construction permits the removal of the plates and in this manner the removal of the 100 shuttle from the guide way. Rollers 21 are 105 arranged on the pins 19 and reduce the friction on the surfaces of the guide ways. The frame 23 has the driver stud 24 and this stud is headed at 25 in the plate 18. A roller 22 is arranged on the stud 24. The 110 bobbin 27 has the central opening 28 into which projects a pin 29 from one end of the frame 23. A spring pin 30 is arranged at the opposite end. The pin 30 extends

through a capped socket 31 and is provided with a knob 32 at its outer end. A washer 33 is secured to the pin 30 adjacent to its inner end and a spring 34 is arranged between the washer 33 and the end of the capped socket 31 and tends to crowd the pin 30 into the opening 28.

The wire 35 passes from the bobbin 27 through a tube 26, the tube extending 10 through the stud 24 and the plates 18 and 17. The wire passes from the tube to the tension wheel 36. The wire is wrapped around the tension wheel 36 a sufficient number of times to prevent any material slipping on the wheel 36. The tension wheel is 15 rotatively mounted on the stud 37, the stud being secured to the plate 17. Friction disks 38 are arranged each side of the wheel 36, and washers 39 are arranged at each side 20 of the disks 38. The nut 40 is screwed on to the stud 37 and by means of it, the friction on the tension wheel 36 may be controlled to give any tension to the wire desired. The wire passes from the tension wheel between 25 the grooved guide pulleys 41. These guide pulleys are mounted on the pins 41^a and the plate 41^b extends from one pin 41^a to the other, thus preventing any possibility of the escape of the wire from between the grooved 30 guide pulleys 41.

The shuttles are mounted on the guide ways with one plate on each face of the plates 3 and 6 and are held in place by the pins 19. They are forced through the guide 35 ways by a driving device so as to traverse the figure 8 guide way and thus wrap the wire alternately on the pins 13 so as to form figure 8 coils, the shuttles passing from one loop of the guide way to the other through 40 the space 15 and drawing the wire over the deflecting plate 14 on to the pins 13. The loops are formed at the rear end of the pins 13 and as each loop is formed, it is crowded in between the preceding loop and the deflecting plate at the base of the pin 13. In 45 this way, the loops are constantly forced off the pins 13, in the form of figure 8 coils, the axis of these coils being lengthwise of the fabric as it is forced off the pins. Where 50 several shuttles are used, as in the machine illustrated, these coils may be interlocked at the edges as clearly shown in the fabric shown in Fig. 7.

As before stated, this machine is arranged 55 to form the fabric 43 of three wires as shown in Fig. 7 and, therefore, has the three shuttles 16^a, 16^b and 16^c carrying the wires 42^a, 42^b and 42^c respectively.

In order to prevent the outward swinging 60 of the wires and consequent wrapping outside of the base of the pins, I provide the guide plates 44 spaced outwardly slightly from the deflecting plates 14. These are mounted on the bars 45 extending upwardly 65 from the base plate and have the outwardly

bent lip 46 so as to assure the ready entry of the wires between the plate 44 and the plate 14. Drivers 47 are provided with the arms 48 in which are arranged the notches 49. The hubs 50 of the drivers are secured on the hubs 51 of the gears 52. The gears 52 are journaled on the shaft 7 so that the drivers rotate with this shaft as an axis. The guide ways 5 are circular in form so that the engaging notches 49 traverse approximately 75 the centers of these guide ways. The roller 22 on the shuttles enters the notches 49 on the arms 48, and the drivers in this way form a driving connection with the shuttles. The two gears 52 are in mesh so that the two 80 drivers are kept in constant relation to each other and the arms of the drivers are so arranged with relation to each other that they reach the crossing of the guide ways 5 so that the roller 22 is in mesh with the notch 49 in both drivers at the same time so that as the shuttle is delivered from one loop of the guide way, it is engaged by the driver of the receiving loop before it is disconnected from the driver of the discharging loop. 85 This position of the parts is clearly shown in dotted lines in Fig. 3. In this way, the shuttles are constantly engaged throughout their travel and at all times are maintained in the exact relation to each other so that the 90 wire is given exactly the right movement and each wire with relation to the others. 95

One of the gears 52 is secured to a gear 55 by bolts 54. The gear 55 meshes with a gear 56. The gear 56 is fixed on the shaft 57 by 100 means of a set screw 58. The shaft 57 is journaled in bearings 59 extending from the base 1 between the legs 2. The shaft 57 is driven by the drive pulley 60, and the drive pulley 60 is driven from any convenient 105 source of power.

As the fabric is forced off the pins 13, the loops have their axes longitudinally of the fabric. In order to form it for use as a garment stay, it is necessary to crush it or bend 110 it so that the axes of the loops are practically at right angles to the line of the fabric. I prefer to accomplish this by a series of crushing rolls 62, 63 and 64. These rolls are journaled on the shafts 65, 66 and 67 respectively, and the journals 65, 66 and 67 are carried in bearings 68, 69 and 70 respectively. These bearings are carried by the frame 71 extending upwardly from the base plate 1 and secured thereto by bolts 72. One 120 of the shafts of each set of rolls is provided with a beveled gear. The shafts on the rolls 62, 63 and 64 have the gears 73, 74 and 75 respectively. Gears 76, 77 and 78 mesh with the gears 73, 74 and 75 respectively 125 mounted on a shaft 79. The shaft 79 is mounted in the bearings 80 extending from the frame 71. A sprocket wheel 81 is fixed on the shaft 79 and a chain 82 connects the sprocket wheel 81 with a sprocket wheel 83. 130

The sprocket wheel 83 is fixed on the shaft 57 and in this way, the rolls 62, 63 and 64 are driven.

In order to stretch the fabric so as to give to the loops the relation one to the other desired, it is necessary to provide a stretching device and this preferably operates to stretch the fabric while it is being held by the crushing device, the fabric passing from the crushing rolls between the stretching rolls 84. These rolls are mounted on the shafts 85, and the shafts are carried in the bearings 86. The bearings 86 are mounted in the frame 71. One of the shafts 85 is mounted between it and the ratchet wheel 87. A ratchet plate 88 is journaled on the same shaft. It carries the ratchet pawls 89 which are forced into engagement by the springs 90. These pawls are mounted on the pins 89^a and have a slightly different spacing than the ratchet wheel so that the pawls drop into engagement successively and thus prevent lost motion between the plate and the ratchet wheel. A rocker arm 91 is pivoted on the plate by means of a pin 92. The arm is provided with a stop 93 which limits its movement in one direction and a screw 94 which acts as a stop to limit its movement in the opposite direction. By adjusting the screw 94, the length of free movement of the rocker arm is controlled and consequently the feeding movement may be thus adjusted. A link 95 is connected to the rocker arm by a pin 96. The link 95 is connected with the eccentric rod 98 by a pin 97. The eccentric rod 98 terminates in the eccentric strap 99. The strap is journaled on the eccentric 100 which is mounted on the shaft 57. In this way, the plate 88 is reciprocated with each revolution of the shaft 57 and the stretching rolls 84 are thus rotated. The amount of rotation and consequently, the amount of stretch given to the fabric is controlled by the set screw 94.

It will be noted that the rolls 63 and 64 are of conical shape but on parallel axes. For this reason only the larger ends of the rolls are in contact or operate upon the fabric as it passes through the rolls. It will also be noted that these sets of rolls are arranged in reverse relation. This form of roll which operates only on one edge at a time is much more effective for some types of fabric, especially the single wire fabric shown in Fig. 8, than the cylindrically shaped rolls operating upon the entire fabric. These conical rolls will stretch one edge, and lay the loops down one after the other effectively where the cylindrical roll would almost entirely fail to effect the result.

What I claim as new is:

1. In a wire bending machine, the combination of two coil-forming pins; a wire-carrying shuttle; and a driving device for said shuttle for carrying the wire from said shut-

tle around said pins to form figure-8 coils, said device comprising means for maintaining a constant driving connection throughout the travel of the shuttle.

2. In a wire bending machine, the combination of two coil-forming pins; a wire-carrying shuttle; and two rotary drivers for actuating said shuttle to carry the wire around said pins to form figure-8 coils, said drivers simultaneously engaging said shuttle through a part of their travel.

3. In a wire bending machine, the combination of two coil-forming pins; a wire-carrying shuttle; and two rotary drivers for actuating said shuttle to carry the wire around said pins to form figure-8 coils, said drivers simultaneously engaging said shuttle through a part of their travel, and said shuttle being continuously engaged throughout its travel by one or the other of said drivers.

4. In a wire bending machine, the combination of a figure-8 guide-way; coil-forming pins at the crossing of the guide-way; a wire-carrying shuttle arranged to travel in the guide-way; and a driving device for said shuttle for carrying the shuttle around said guide-way to form figure-8 coils on said pins, said device comprising means for maintaining a constant driving connection with the shuttle throughout the travel of the shuttle.

5. In a wire bending machine, the combination of a figure-8 guide-way; coil-forming pins arranged at the crossing of the guide-way; a wire-carrying shuttle arranged in the guide-way; and two rotary drivers for actuating said shuttle in the drive-way to carry the shuttle through the guide-way around the pins to form figure-8 coils, said drivers simultaneously engaging said shuttle through a part of the travel.

6. In a wire bending machine, the combination of a figure-8 guide-way; coil-forming pins arranged at the crossing of the guide-way; a wire-carrying shuttle arranged in the guide-way; and two rotary drivers for actuating said shuttle in the drive-way to carry the shuttle through the guide-way around the pins to form figure-8 coils, said drivers simultaneously engaging said shuttle through a part of the travel, said shuttle being continuously engaged throughout its travel by one or the other of said drivers.

7. In a wire bending machine, the combination of two coil-forming pins; a plurality of wire-carrying shuttles; and a driving device for said shuttles for carrying the wires from said shuttles alternately around said pins to form figure-8 coils, said devices comprising means for maintaining a constant driving connection with each shuttle throughout the travel of the shuttle.

8. In a wire bending machine, the combination of two coil-forming pins; a plurality of

- of wire-carrying shuttles; and two rotary drivers for actuating said shuttles to carry the wire alternately around said pins to form figure-8 coils, said drivers simultaneously engaging each shuttle through a part of its travel.
9. In a wire bending machine, the combination of a figure-8 guide way; a plurality of wire-carrying shuttles arranged in said 10 guide-way; and a driving device for said shuttles for carrying the wires from said shuttles around said pins alternately to form figure-8 coils, said device comprising means for maintaining a constant driving 15 connection between said driving device and the shuttles throughout the travel of the shuttles.
10. In a wire bending machine, the combination of a figure-8 guide-way; a plurality of wire-carrying shuttles in said 20 guide-way; and two rotary drivers for actuating said shuttles to carry the wire from said shuttles alternately around said pins to form figure-8 coils, said drivers simultaneously engaging each shuttle through a part of the path of its travel.
11. In a wire bending machine, the combination of a figure-8 guide way; a shuttle arranged to travel in said guide way; and 25 two rotary drivers for actuating said shuttle, each driver having an arm formed to interlock with the shuttle, the arms being timed to simultaneously interlock with the shuttle at the crossing of the guide way.
12. In wire bending machine, the combination of a figure-8 guide way; a plurality of shuttles in said guide way; two 30 rotary drivers each having a pair of arms corresponding to the number of shuttles; and means carried by the arms for engaging the shuttles and forming a driving connection therewith, said drivers being timed to bring each pair of arms simultaneously into engagement with the same shuttle at the 35 crossing of the guide way.
13. In a wire bending machine, the combination of a guide plate having an opening for forming a figure-8 guide way; center plates for completing the guide way; 40 shafts for the center plate; a shuttle arranged in the guide way; drivers rotatable on the shafts for actuating the shuttle; gears on which the drivers are fixed, said gears being in mesh; a driving gear secured to one of the gears; and means for driving the driving gear.
14. In a wire bending machine, the combination of a figure-8 guide-way; and L-shaped 45 forming pins at the crossing of the guide-way, each of said pins having an outwardly extending portion and a lateral extending attaching portion.
15. In a wire bending machine, the combination of a figure-8 guide way; L-shaped 50 forming pins at the crossing of the guide way, said pins having an outwardly extending portion and a lateral extending attaching portion; and clamps arranged on said attaching portion for securing said pins.
16. In a wire bending machine, the combination of a figure-8 guide way; forming pins arranged at the crossing; and mountings for said pins, one of said mountings being adjustable to vary the distance between the pins.
17. In a wire bending machine, the combination of a figure-8 guide way; forming pins arranged at the crossing; mountings for said pins, one of said mountings being slotted; a screw arranged in said slot; and an adjusting screw for adjusting the mounting laterally to vary the distance between the pins.
18. In a wire bending machine, the combination of a figure-8 guide way; forming 55 pins at the crossing; a shuttle mounted in the guide way arranged to carry the wire around said pins; and a plate in front of the guide way and spaced therefrom to prevent the outward movement of the loops of 60 wire as they are formed.
19. In a wire bending machine, the combination of devices for forming coils with 65 their axes lengthwise of the resulting fabric; and crushing rolls for flattening the coils as they come from the coil forming 70 device.
20. In a wire bending machine, the combination of two coil-forming pins; means 75 acting with the pins for forming figure-8 coils on said pins with the axes of the coils extending lengthwise of the fabric; and coil flattening rolls to which the coils pass from the forming pins.
21. In a wire bending machine, the combination of devices for forming coils with 80 their axes lengthwise of the resulting fabric; crushing rolls to which the coils pass from the devices for forming the coils for 85 flattening the coils; and a stretching device 90 for stretching the fabric as it passes from the flattening rolls.
22. In a wire bending machine, the combination of two coil forming pins; means 95 acting with the pins for forming figure-8 coils on said pins with the axes of the coils extending lengthwise of the fabric; coil flattening rolls to which the coils pass from the forming pins; and a stretching device 100 for stretching the fabric as it passes from 105 the flattening rolls.
23. In a wire bending machine, the combination of a coiling device; a flattening device; and a stretching device, comprising 110 rolls for drawing the fabric forward; means 115 for actuating the stretching rolls; and means for adjusting the movement of the stretching rolls relatively to the formation of the fabric to vary the stretching movement.
24. In a wire bending machine, the com- 120

5 combination of a coiling device; a flattening device; and a stretching mechanism comprising rolls for drawing out the fabric; a ratchet wheel for driving said rolls; a pawl carrier; means for oscillating the pawl carrier; and means for adjusting the throw of the pawl carrier to vary the feed movement.

10 25. In a wire bending machine, the combination of a coiling device; a flattening device; and a stretching mechanism comprising rolls for drawing out the fabric; a ratchet wheel for driving said rolls; a pawl carrier; means for oscillating the pawl carrier; a rock arm secured to the pawl carrier; 15 an adjustable stop on the rock arm; and means for actuating the rock arm to actuate the pawl carrier.

20 26. In a wire bending machine, the combination of a coil forming device; and a flattening device comprising conical rolls, the larger ends of the rolls being at the same side of the stay whereby one edge of the stay is subjected to greater pressure than the other.

25 27. In a wire bending machine, the combination of a coil forming device; and a flattening device comprising two sets of conical rolls, the larger ends of the rolls of each set being opposed to each other, one set being in 30 reverse relation to the other.

35 28. In a wire bending machine, the combination of devices for forming figure-8 coils; and a flattening device comprising conical rolls, the larger ends of the rolls being at the same side of the stay whereby one edge of the stay is subjected to greater pressure than the other.

40 29. In a wire bending machine, the combination of devices for forming figure-8 coils; and a flattening device comprising two sets of conical rolls, the larger ends of the rolls of each set being opposed to each other, one set being in reverse relation to the other.

45 30. In a wire bending machine, the combination of two flattening rolls, one of which is conical; and means for driving one of said rolls, the conical rolls exerting greater pressure on one edge of the stay than the other.

50 31. In a wire bending machine, the combination of two flattening rolls, both of which are conical; and means for driving one of said rolls, the larger ends of the rolls being at the same side of the stay whereby one edge of the stay is subjected to greater pressure than the other.

55 32. In a wire bending machine, the combination of two sets of flattening rolls, each 60 set comprising one conical roll, greater pressure being exerted on the stay at the edge operated upon by the larger end of the conical roll, and the conical roll of one set being ar-

ranged in reverse relation to the conical roll of the other set.

65

33. In a wire bending machine, the combination of two sets of conical flattening rolls, the larger ends of the rolls of each set being opposed to each other, the rolls of one set being arranged in reverse relation to the 70 conical rolls of the other set.

34. In a wire bending machine, the combination of a guide way; a shuttle arranged in the guide way; a spool carrying device on the shuttle; a tension device carried by the 75 shuttle, comprising a tension wheel around which the wire is wrapped; and means for exerting friction on the tension wheel.

35. In a wire bending machine, the combination of a guide way; a shuttle arranged 80 in the guide way; a spool carrying device on the shuttle; a tension device carried by the shuttle, comprising a tension wheel around which the wire is wrapped; and an adjustable means for exerting friction on the ten- 85 sion wheel.

36. In a wire bending machine, the combination of a figure-8 guideway; coil-forming pins at the crossing; a shuttle arranged in a guideway; means for driving the 90 shuttle; a bobbin on the shuttle; a tension device comprising a wheel around which the wire is wrapped; and means for exerting friction on the wheel.

37. In a wire bending machine, the combination of a guideway; plates arranged at each side of said guideway; a bobbin frame; a pin connection between said frame and one of said plates; and a driving device for said shuttle adapted to engage said pin connec- 95 100 tion.

38. In a wire bending machine, the combination of a guideway; a shuttle comprising plates arranged on the face of the guideway; pins extending between said plates and detachably secured to one of said plates; and a bobbin carrier carried by one of said plates. 105

39. In a wire bending machine, the combination of a coil forming device; and a flattening device comprising rolls formed to exert greater pressure on one edge than the other.

40. In a wire bending machine, the combination of a coil forming device; and a flattening device formed of a plurality of sets 110 115 of rolls arranged to exert alternately greater pressure on one edge of the fabric than the other.

In testimony whereof I have hereunto set my hand in the presence of two subscribing 120 witnesses.

JOHN R. DEAN.
